UNITED STATES PATENT OFFICE.

MORRIS ROSENWASSER, OF NEW YORK, N. Y.

LEGGING.

945,420.

Specification of Letters Patent.

Patented Jan. 4, 1910.

Application filed January 22, 1909. Serial No. 473,700.

To all whom it may concern:

Be it known that I, MORRIS ROSENWASSER, residing at New York, in the county of New York and State of New York, have invented 5 certain new and useful Improvements in Leggings, of which the following is a specification.

This invention relates to garments and more particularly to leggings.

10 One of the objects of the invention is to provide means whereby the application of the legging is facilitated and its fit about the leg and foot improved, the said means comprising essentially a stirrup fixedly se- 15 cured to the legging body and to one of the flaps, and detachably secured to the other flap, together with means for inducing an operative strain between the stirrup and the upper part of the legging.

20 In the art heretofore it has been customary to secure the stirrup only to the lower edge of the legging body and to one of the meeting flaps thereof. By such construction it is impossible to achieve the desired snug 25 connection of the lower end of the legging to the foot, one of the flaps having no direct union with the stirrup. By my invention the entire lower end of the legging attaches to the stirrup, so that it is snugly drawn down 30 to and maintained in position about the foot on all sides. Furthermore, by making the detachable connection of the stirrup to one of the flaps adjustable, it is possible to vary in some measure the operative length of the 35 stirrup, so that the lower edges of the legging may be drawn as closely down to the foot as desired.

It is a further object of the invention to provide a stirrup having the capacities above 40 set out, at but very little more expense than that of the ordinary form, and just as easily assemblable with the legging.

Still another object of the invention is to so form that part of the stirrup which is 45 detachable that it constitutes a hand-hold in the operation of inserting the foot.

Another object is to produce a strain between the stirrup and the upper part of the legging, so that a snug fit of all the parts is 50 constantly maintained in the stirrup.

Other aims of the invention will be referred to or appear in the course of the following specifications, wherein the elements, combinations, and arrangements of parts

constituting the invention, will be fully de- 55 scribed, the scope of the application thereof being indicated by the appended claims.

In the accompanying drawings, which are to be taken as a part of this specification, and in which I have illustrated a merely preferred 60 form of embodiment: Figure 1 is a perspective showing a legging equipped with my improvement, as in position upon the leg; and Fig. 2 is a sectional view, partly broken away, showing my improved stirrup and the 65 manner of its connection with the legging.

Similar reference characters mark like parts throughout.

Referring now more specifically to the drawings, my invention is shown applied to 70 a puttee legging indicated at 1, which in its general features is of any usual or preferred construction. One novel feature of my construction, however, should be referred to here. This is the cutting away of the lower 75 forward corner of the outer flap, as indicated at 9, the inner flap, which is of full extent, serving by itself to cover the instep, thus avoiding undesirable multiplication of thickness of material over the instep. The said 80 cut-out 9 is so located that when the legging is in place the lower forward edge of the outer flap is positioned just above the instep. The reason for this arrangement will be developed presently. 85

The legging is adapted to be placed about the leg, the free vertical edges 2 and 3 coming at the side portion of the legging and preferably lapping one upon the other. Any usual means for fastening the legging about 90 the leg may be employed. In the present case I have shown a strap fastened at the upper and lower portions of the legging, passing spirally about the same, and maintained in proper position by guide-loops. 95 Said strap is secured at one end to the outer flap at the lower forward cut out part 9 thereof. The adjustable connection of the stirrup, hereinafter described, being also at this part 9, and substantially in alignment 100 with the fastening of said strap, it follows that if said flap be, by the adjustable connection of the stirrup therewith, drawn toward the stirrup; and if also the spiral strap be drawn up about the leg, the outer flap will 105 by the opposing strains be drawn taut along the part 9, so that there will be a snug fit of the outer flap over and above the instep.

Thus there is a direct and advantageous relation between the device which secures the legging to the foot (the stirrup), and the device which secures it about the leg (the winding strap).

5 4 indicates a stirrup, comprising a strip of suitable material, doubled upon itself as indicated at 5. This doubled strip is secured to the body of the legging at the lower edge thereof, at a point approximately opposite the meeting line of the edges 2 and 3, said point being indicated in Fig. 2 by the numeral 6. The strip extends from this point 6 under and across the legging, the 10 superposed sections 7 and 8 being preferably sewed together through a part of their extent to constitute the stirrup member proper. At some suitable point, as 10, the members 7 and 8 are freed of this superposed union, and diverge, member 7 extending and 15 being securely fastened to the inner flap 11 of the legging, while the member 8 extends out for detachable connection with the outer flap 12. As shown, for the sake of strength 20 in a part that is subjected to considerable manipulation, I prefer to make the member 8 of such length that it may be doubled upon itself, the superposed parts being sewed together, and the end extending up to the 25 point where the members 7 and 8 separate. Thus it will be seen that there is formed a stirrup-strap double-thick throughout its extent, of a single piece of material, and yet 30 having the integral extension 14.

35 It has been stated that the doubled end 15 of member 8 is adapted to be detachably connected to the outer flap 12. To this end I may provide a swing buckle 16 pivoted in a loop 17 secured to flap 12, there being also 40 a keeper 18.

In the use of the device it will be seen that the body of the legging is always connected with the flap 11 by means of the stirrup and extension 7. The legging is thus in a 45 measure ready-shaped, and is easily manipulated in putting it on. The end 15 is of course free from engagement with buckle 16, and it is necessary, after the foot has been inserted in the stirrup, to engage the end 15 50 with the buckle, thus directly connecting the lower edge of the legging body with the lower edges of the flaps 11 and 12. The fastening of the legging about the leg is accomplished by means of the spirally arranged 55 strap heretofore referred to. The effect of drawing the flap toward the stirrup, by means of buckle 16 and drawing it in the opposite direction by means of the spiral strap, has already been explained.

60 It may be noted, as a preferred construction, and as furthering the object last referred to besides subserving the unification of the garment as a whole when applied, that the winding strap is affixed at the lower end 65 to one flap (here the outer flap), and at the

other end to the other flap, the connection to said last named flap being detachable, as by means of the buckle 19 shown in Fig. 1.

As many changes could be made in the above construction and many apparently 70 widely different embodiments of this invention could be made without departing from the scope thereof, it is intended that all matter contained in the above description or shown in the accompanying drawing shall 75 be taken as illustrative, and not in a limiting sense. It is also to be understood that materials, sizes, and relativities of parts, are unimportant, except as they are called for in the following claims, which define the 80 scope of invention contemplated.

Having described my invention what I claim as new and desire to secure by Letters Patent is:

1. A legging adapted to be placed about 85 the leg, and a one piece stirrup attached to the lower edge of the legging at a plurality of more than two points, the connection at one of said points only being detachable.

2. A legging adapted to be wrapped about 90 the leg and having meeting flaps, a one piece stirrup fixedly secured to the said legging and to one of said flaps, and provided with means for connecting it detachably to the other flap.

3. A legging adapted to be wrapped about 95 the leg and having meeting flaps, a one piece stirrup secured to the said legging and to one of said flaps, and provided with means for connecting it adjustably to the other flap.

4. A legging adapted to be wrapped about 100 the leg and having meeting flaps, a one piece stirrup secured to the said legging and to one of the flaps and provided with means for connecting it detachably to the other 105 flap, a strap secured to said last named flap adjacent to the point of said detachable connection and adapted to wind spirally about the legging, and means for securing the strap at the upper end of the legging. 110

5. A legging adapted to be wrapped about 115 the leg and having meeting flaps, a one piece stirrup secured to the said legging and one of the flaps and provided with means for connecting it detachably to the other flap, a strap secured to said last named flap adjacent to the point of said detachable connection and adapted to wind spirally about the legging, said flaps being provided with keeper-loops for said strap, and means for 120 securing the strap at the upper end of the flap opposite the one to which it is secured at the lower part of the legging.

6. A legging provided with meeting flaps, a one-piece stirrup secured positively to the 125 body of the legging and to one of said flaps, and having an integral extension connected detachably to the other flap.

7. A legging provided with meeting flaps, a one-piece stirrup secured positively to the 130

body of the legging and to one of said flaps, and having an integral extension connected to the other flap, the connection to one of said flaps being detachable and attachable.

5 8. A legging provided with a pair of meeting flaps, a stirrup comprising a strip of material whose ends are doubled upon it toward the middle and secured to it, one of said ends extending free of the doubled body from the middle, one end of said strip being connected to the legging body, and the other end and the extension being connected, respectively, to the said flaps.

9. A legging provided with a pair of meeting flaps, a stirrup comprising a strip of material whose ends are doubled upon it toward the middle and secured to it, one of said ends extending free of the doubled body from the middle, one end of said strip being connected to the legging body, and the other end and the extension being connected, respectively, to the said flaps.

15 20. A legging provided with a pair of meeting flaps, a stirrup comprising a strip of material whose ends are doubled upon it toward the middle and secured to it, one of said ends extending free of the doubled body from the middle, one end of said strip being connected to the legging body, and the other end and the extension being connected, respectively, to the said flaps.

connected, respectively, to the said flaps, one of said last named connections being detachable.

10. A legging provided with a pair of 25 meeting flaps, a stirrup comprising a strip of material whose ends are doubled upon it toward the middle and secured to it, one of said ends extending free of the doubled body from the middle, one end of said strip being 30 connected to the legging body, and the other end and the extension being connected, respectively, to the said flaps, the first of said last named connections being adjustable and detachable.

35 In testimony whereof I affix my signature in the presence of two witnesses.

MORRIS ROSENWASSER.
